TUCKING ASSEMBLY FOR SEWING MACHINES

Leonard Coiner, Winnipeg, Manitoba, Canada

Application March 8, 1956, Serial No. 570,261

11 Claims. (Cl. 112—132)

My invention relates to new and useful improvements in tucking assemblies for sewing machines, the principal object and essence of my invention is to provide a device of the character herewithin described which includes a pair of tucking feet forwardly of the conventional foot assembly, said feet adapted to have a substantially rotary motion and to operate alternatively so that they contact the surface of the material thereby gathering same preparatory to passing same under the conventional foot for sewing.

Another object of my invention is to provide a device of the character herewithin described which is particularly suitable for use with leather and the like thereby facilitating the sewing of the vamp of a shoe or slipper to the remaining portion of the shoe.

Another object of my invention is to provide a device of the character herewithin described which facilitates the making of slippers or moccasins by permitting the entire sewing operation to be done by machine instead of partly by hand.

Another object of my invention is to provide a device of the character herewithin described which permits the degree of gathering or tucking to be controlled and adjusted readily.

Another object of the invention is to provide a device of the character herewithin described which is easily attached to conventional sewing machines.

Another object of the invention is to provide a device of the character herewithin described which, due to its construction, permits the machine to be run at normal speed.

Another object of the invention is to provide a device of the character herewithin described which is also simple in construction, economical in manufacture, and otherwise well suited to the purpose for which it is designed.

With the foregoing objects in view, and such other objects and advantages as will become apparent to those skilled in the art to which this invention relates as this specification proceeds, my invention consists essentially in the arrangement and construction of parts all as hereinafter more particularly described, reference being had to the accompanying drawings in which:

Figure 1 is a side elevation of my device.

Figure 2 is a top plan view of my device.

Figure 3 is a view showing the vamp and a portion of the remainder of the shoe to illustrate the amount of gathering required in order to sew one to the other.

In the drawings like characters of reference indicate corresponding parts in the different figures.

In the manufacture of leather slippers or moccasins, it is usual to form the sole and main body of the shoe or slipper from one piece of leather which necessitates a vamp portion to cover the toes and instep. In order to form the main portion in order to give substantially vertical wall around the front of the foot, it is necessary to gather a considerable amount of the material when inserting the vamp therein.

2

While it is well known that tucking attachments are available for use with sewing machines, nevertheless these are only usable with fabrics having a relatively small inherent resistance to gathering. However, when a relatively stiff leather is used, this gathering or tucking is normally done by hand and the stitching of the vamp to the main portion of the shoe is also of course done by hand. This is extremely time consuming and, unless particular care and skill is taken, the results are unsightly due to the difficulty of working a relatively thick material such as leather.

The present device overcomes these disadvantages and gathers the material of the main portion of the shoe just prior to its being sewn to the vamp in such a fashion that the amount to be lost or gathered is distributed evenly completely around the stitch line. As an example of the amount of material to be gathered, in a conventional slipper the perimetrical length of the stitch line which is equivalent to the perimetrical length of the vamp is approximately eight inches whereas the perimetrical length of the portion of the shoe to be sewn to the vamp is, prior to sewing, approximately 13½ inches so that some 5½ inches of material has to be gathered and absorbed during the stitching of the 8-inch stitch line.

Proceeding, therefore, to describe my invention in detail, I have shown in Figure 1 one end 10 of the head of a conventional sewing machine having an arm assembly 11, therebelow and a conventional foot assembly 12, extending from the head and adapted to operate upon the arm 11 in the conventional manner.

My device collectively designated 13 is situated behind the head and foot of the machine supported upon a surface 14 which may be a part of the table of the conventional sewing machine.

Upon this supporting surface 14 is a drive shaft 14' journalled for rotation within bearings 15 secured to the surface 14 and having a pulley 16 secured to the shaft whereby the shaft may be rotated from the source of power adapted to operate the sewing machine 10. A pair of off-set crank pin bearings 17 and 18 are secured to shaft 14', the throws of these crank pin bearings being diametrically opposite and a crank shaft end 19 surrounds each of these crank pin bearings. Crank shafts 20 and 21 are secured to the perimeters 22 of the ends 19 by means of sleeves 23 within which the crank shafts are screw-threadably received.

From the foregoing it will be appreciated that rotation of the shaft 14' will cause the crank shafts 20 and 21 to reciprocate in the direction of the double-headed arrow 24 and with opposite throws. The forward ends 25 of the crank shaft are provided with fork ends 26 which are adapted to engage around a pair of rocking bars 27 and 28. Each of these rocking bars consists of a substantially vertical strip open centred as at 29 and thumb screws 30 pass the fork ends so that the fork ends can be clamped to the rocking bars along the length thereof depending upon the throw required.

A bearing block collectively designated 31 is provided for each of said rocking bars, each bearing block including an upper surface portion 32 and a downwardly extending portion 33. Each bearing block is pivotally mounted by pin 34 upon a bracket 35 secured to the arm 11 of the sewing machine immediately behind the foot assembly 12. Each rocking bar includes a forwardly extending lug 36 formed intermediate the ends thereof, but slightly towards the lower end 37 of the bar and a bolt 38 secures the rocking bars via the lugs 36 to the aforementioned bearing blocks 31 upon the downwardly depending portion 33 thereof.

From the foregoing it will be appreciated that the positioning of the fork ends 26 of the crank shaft upon the rocker arms will vary the throw of the rocker arms inas-

much as the higher up the rocker arm the fork ends are secured, the smaller the throw and the closer towards the lugs 26, the greater the throw. It will also be appreciated that rotation of shaft 14' will cause the bearing blocks 31 to rock to and fro upon their pivot 34.

A pair of tucking foot assemblies collectively designated 39 are secured to the upper surfaces 32 of the bearing blocks 31, each tucking foot assembly including a substantially horizontal main portion 40 consisting of a bar held within upstanding guides 41 formed upon the aforesaid upper surface 32 of the bearing blocks, pivot pins 42 permitting pivotal connection of the main portions 40 within the guides 41. Secured to and extending forwardly from the forward ends 43 of each of the main portions by means of bolt 44, is a material tucking end 45 which consists of a bar 46 angulated as at 47 and having a downwardly inclined end portion 48 secured thereto by means of set screws 49.

Reference to Figure 2 will show that the material tucking ends vary in length so that one can pass behind the other and at the same time the actual engaging dogs 50 can operate side by side and adjacent the surface of the arm 11 as clearly shown in Figure 2.

From the foregoing it will be appreciated that rotation of the shaft 14' will cause a substantially horizontal reciprocation of the engaging dog 50 substantially parallel with the surface of the arm 11. However, it is also desirable that vertical reciprocation of the dogs be provided so that the resultant motion thereof is substantially circular and alternative and in this connection I have provided an angulated rear end 51 to each of the main portions 40 of the tucking feet, said end angulating upwardly as clearly shown in Figure 1.

An actuating strip 52 is provided for each of said angulated portions 51, said actuating strip including a substantially vertical portion 53 secured to the upwardly angulated ends 51 in the main portions by means of bolt assemblies 54. These actuating strips extend downwardly and then rearwardly to form the substantially horizontal portions 55, the rear ends 56 of which are engageable by a tension spring 57 extending upwardly and which in turn is anchored by adjustable bolt 58 to supporting bracket 59 secured to the main supporting table 14, it being understood that springs 57 normally maintain the ends 56 biased upwardly.

Also secured to shaft 14' is a sprocket 60 engageable by sprocket chain 61 which also extends over a sprocket 62 carried upon a stub shaft 63 supported for rotation between bearings 64 also secured to main table 14 between the shaft 14' and the rocking bars 28 and 29.

This shaft 63 is provided with cams 65 having throws 66 oppositely formed as clearly shown in Figure 2, these cams being engageable at all times with actuating strips 52.

It will therefore be appreciated that rotation of shaft 63 will cause cams 65 to rock the actuating strips 52 substantially in the direction of double-headed arrow 66 and hence will cause the dogs 50 to reciprocate alternatively substantially in a vertical manner. By timing the actuation of the cams 65 and the crank shafts 20 and 21, it will be apparent that the dogs 50 can be made to trace a substantially circular path in the direction of arrow 67 and due to the fact that the crank shafts and the cams are situated oppositely, the dogs 50 will have an alternative action. In other words, when one dog 50 is engaging the material and drawing it rearwardly, against the foot 12, the other dog is moving forwardly to engage material behind the first dog.

It is this alternative engaging action of the dogs 50, which are slightly edge-sharpened for traction, which gathers the material prior to its being passed under the foot 12 and it will be appreciated that the amount gathered by each motion of the dogs 50 is controlled by the throw of the rocking arms.

It is also necessary to provide feed dogs 67 underneath the material passing below the foot 12 and I have provided a feed dog for each material engaging foot.

Each of these feed dogs consists of an elongated strip 5 situated within guides 68 formed in the surface of the arm 11. These strips extend forwardly and are pivotally secured to the upper ends of a pair of actuating levers 69 pivoted intermediate the ends upon lugs 70 extending downwardly from the arm 11.

10 The lower ends 71 of the actuating levers are in turn pivotally connected to the forward ends 72 of a pair of links 73 reciprocating below the arm 11.

The rear ends 74 of the length 73 are secured to the lower ends 37 of the aforementioned rocking arms 27 15 and 28 as clearly illustrated in the drawings so that reciprocation of the feed dogs 67' is also alternative and timed with the gathering action of the tucking feet.

Figure 3 shows a front top plan view of a slipper or moccasin partly formed and includes the relatively flat vamp 75 and the main portion 76 which normally is manufactured in one piece with the sole 77. A stitch line 78 secures the two portions together but in order to shape the forward perimeter 79 of the main portion around the toes of the foot, it is necessary to gather or 25 tuck the perimetrical edge 80 of this portion as it is secured to the perimetrical edge 81 of the vamp 75. The hatching 82 indicates the gathering that has been made in sewing from the point 83 to the point 84. The distance between the point 84 and the point 85 on the vamp indicates the further stitching to be undertaken and the 30 distance between 84 and 86 on the perimeter 80 of the main portion indicates the amount of material that has to be lost or gathered during this operation as, when the sewing is finished, point 86 is secured to point 85 and the 35 remaining material is gathered evenly around this distance between points 84 and 85.

With this machine it is possible to undertake this operation evenly and neatly and without loss of time as contrasted to conventional methods of leather working which 40 requires the tucking or gathering to be done by hand and the stitching also.

Finally, I have provided means to stop the tucking action temporarily without stopping the sewing machine comprising a chain or cable 87 secured to adjacent the 45 rear ends of actuating strips 52 and extending to adjacent the operator. These cables are connected to conventional foot pedal or knee pedal linkage (not illustrated) and when actuated, draw down the strips 52 against pressure of springs 57 thus disengaging the strips 50 from cams 65 and at the same time raising the tucking dogs 50 clear of the surface of the material. Being clear 55 of the cams, the strips are not actuated thereby and hence no vertical reciprocal motion is imparted to the tucking dogs. This is useful if the material tends to bunch up in advance of the foot 12 as sometimes happens particularly when sewing around a curve.

Since various modifications can be made in my invention as hereinabove described, and many apparently widely different embodiments of same made within the 60 spirit and scope of the claims without departing from such spirit and scope, it is intended that all matter contained in the accompanying specification shall be interpreted as illustrative only and not in a limiting sense.

What I claim as my invention is:

65 1. In a machine including a head, an arm below said head, and a foot assembly extending between said head and towards said arm, a tucking assembly co-operating with said foot assembly adapted to gather material preparatory to passing same under said foot for securing; said tucking assembly including drive means therefore, a pair of substantially side by side rocking bars mounted intermediate the ends thereof, a bearing block for each bar pivotally mounted upon said arm, each of said bars being mounted upon one of said bearing blocks, crank shafts extending between each of said bars and said drive.

means, each of said crank shafts having diametrically opposite throws, a tucking foot secured to each of said bearing blocks above said pivotal mounting thereof, each of said tucking feet including a downwardly curved material tucking end situated adjacent the surface of said arm, the rocking of said bars adapted to transmit substantially horizontal reciprocal motion to said material tucking ends, and means operatively connected with said tucking feet adapted to impart substantially vertical reciprocal motion to said material tucking ends, said last mentioned means being operatively connected to said drive means, the timing of said horizontal and vertical reciprocation adapted to resolve said horizontal and vertical reciprocation into a substantially circular motion.

2. The device according to claim 1 which includes a feed dog situated in said arm adjacent each of said material tucking ends adapted to reciprocate horizontally, and means extending between the lower ends of said bars and said feed dogs adapted to reciprocate said feed dogs.

3. The device according to claim 1 in which each of said bars is open centred, said crank shaft being secured by one end thereof to said bars, said securement being adjustable vertically upon said bars thereby varying the stroke of the rocking action thereof.

4. The device according to claim 1 in which each of said tucking feet includes a main portion, said material tucking ends being adjustably secured by one end thereof to one end of said main portion, the other end of said main portion being angulated upwardly, said means to impart substantially vertical reciprocal motion to said material tucking ends including an actuating strip secured by one end thereof to said angulated end, said actuating strip extending downwardly and then rearwardly from said angulated end, spring means secured to the rear ends of each of said actuating strips normally biasing said rear end upwardly and hence said material actuating ends downwardly, and cam means actuated by said drive means contacting said actuating strips, adapted to depress said actuating strips, against said spring means hence raising said material contacting end.

5. The device according to claim 2 in which each of said bars is open centred, said crank shaft being secured by one end thereof to the lower end of each of said bars, said link passing below said feed dogs, guides within said arms, actuating levers pivoted intermediate the ends thereof to said arms, one end of said actuating lever being pivotally secured to one end of said link, the other end of said actuating lever being secured to said feed dogs.

6. The device according to claim 2 in which each of said bars is open centred, said crank shaft being secured by one end thereof to said bars, said securement being adjustable vertically upon said bars thereby varying the stroke of the rocking action thereof.

7. The device according to claim 2 in which each of said tucking feet includes a main portion, said material tucking ends being adjustably secured by one end thereof to one end of said main portion, the other end of said main portion being angulated upwardly, said means to impart substantially vertical reciprocal motion to said material tucking ends including an actuating strip secured by one end thereof to said angulated end, said actuating strip extending downwardly and then rearwardly from said angulated end, spring means secured to the rear ends of each of said actuating strips normally biasing said rear end upwardly and hence said material actuating ends

downwardly, and cam means actuated by said drive means contacting said actuating strips, adapted to depress said actuating strips against said spring means hence raising said material contacting end.

5 8. The device according to claim 3 in which each of said tucking feet includes a main portion, said material tucking ends being adjustably secured by one end thereof to one end of said main portion, the other end of said main portion being angulated upwardly, said means to impart substantially vertical reciprocal motion to said material tucking ends including an actuating strip secured by one end thereof to said angulated end, said actuating strip extending downwardly and then rearwardly from said angulated end, spring means secured to the rear ends of each of said actuating strips normally biasing said rear end upwardly and hence said material actuating ends downwardly, and cam means actuated by said drive means contacting said actuating strips, adapted to depress said actuating strips against said spring means hence raising said material contacting end.

20 9. The device according to claim 5 in which each of said bars is open centred, said crank shaft being secured by one end thereof to said bars, said securement being adjustable vertically upon said bars thereby varying the stroke of the rocking action thereof.

25 10. The device according to claim 5 in which each of said tucking feet includes a main portion, said material tucking ends being adjustably secured by one end thereof to one end of said main portion, the other end of said main portion being angulated upwardly, said means to impart substantially vertical reciprocal motion to said material tucking ends including an actuating strip secured by one end thereof to said angulated end, said actuating strip extending downwardly and then rearwardly from said angulated end, spring means secured to the rear ends of each of said actuating strips normally biasing said rear end upwardly and hence said material actuating ends downwardly, and cam means actuated by said drive means contacting said actuating strips, adapted to depress said actuating strips against said spring means hence raising said material contacting end.

30 11. The device according to claim 5 in which each of said tucking feet includes a main portion, said material tucking ends being adjustably secured by one end thereof to one end of said main portion, the other end of said main portion being angulated upwardly, said means to impart substantially vertical reciprocal motion to said material tucking ends including an actuating strip secured by one end thereof to said angulated end, said actuating strip extending downwardly and then rearwardly from said angulated end, spring means secured to the rear ends of each of said actuating strips normally biasing said rear end upwardly and hence said material actuating ends downwardly, and cam means actuated by said drive means contacting said actuating strips, adapted to depress said actuating strips against said spring means hence raising said material contacting end.
